SEPARABLE MOVING PICTURE FILM REEL

Nathan E. Goldberg and Jacob M. Goldberg,
Denver, Colo.

Application October 31, 1947, Serial No. 783,332

13 Claims. (Cl. 242—70)

1

This invention relates to improvements in moving picture film reels and has reference more particularly to a reel that can be separated so as to permit the roll of film to be removed therefrom.

In the moving picture industry the films containing the pictures are usually handled and transported while wound on suitable reels which protect the edges of the film and facilitate winding, unwinding and handling.

After a moving picture has been used for a considerable length of time, or after it has been damaged through tearing, etc., it is usually discarded and for this purpose it is removed from the ordinary moving picture film reel onto an inexpensive reel and sometimes stored without the use of a reel being merely held together by suitable wrappings.

In the ordinary moving picture film reel the film can be applied and removed therefrom by winding operation only. When a film has outlived its usefulness for any reason, and is to be put into storage to be held for desilvering or for any other purpose, a large amount of time can be saved if the film can be removed from the reel without rewinding onto another reel.

It is the object of this invention to produce a moving picture film reel of such construction that it can be readily separated into two parts so that a moving picture film wound thereon can be easily removed therefrom and either positioned on a storage reel or otherwise prepared for storage or desilvering.

Another object of the invention is to produce a reel that can be separated and onto which a roll of film can be applied without the usual winding operation.

A further object of this invention is to produce a reel for the purpose above indicated, which shall be so constructed that the sides can be made with a single die, if desired, and which shall be provided with readily releasable locking means that will hold the two parts in assembled relation or release them for separating the roll of film therefrom.

Having thus called attention to some of the objects of this invention and, in a general way indicated the construction of the reel itself, the latter will now be described in detail and for this purpose reference will be had to the accompany-

2

ing drawing in which the invention has been illustrated in its preferred form, and in which:

Figure 1 is a side elevation of a reel constructed in accordance with this invention;

5 Figure 2 is a side elevation similar to that shown in Figure 1, showing the central part of the reel to a somewhat enlarged scale;

Figure 3 is a view taken from the opposite side of the reel from that shown in Figures 1 and 2;

10 Figure 4 is a section taken on line 4—4, Figure 2;

Figure 5 is a section taken on line 5—5, Figure 4;

15 Figure 6 is a section taken on line 6—6, Figure 2;

Figure 7 is a section taken on line 7—7, Figure 2; and

Figure 8 is a section taken on line 8—8, Figure 3.

20 Referring now to the drawing, reference numerals 10 and 11 designate the two sides of the reel. These parts are practically duplicates, each having a centrally depressed portion comprising a cylindrical surface 12 and a flat bottom portion 13.

25 It will be observed that the center portions are slightly offset outwardly so as to provide two circular ridges that have been designated by reference numeral 13a, in Figure 6. The ridges are of such height that the opposed surfaces of bottoms 13 are spaced a sufficient distance to receive the plate 14 which has its center offset to form the hub portion designated by reference numeral 15.

30 The inner edge of the center bottom 13 shown at the under side in Figure 4 is offset outwardly as shown at 16, forming an opening for the reception of flange 17 of hub member 15a, all as shown in Figure 4. The annular flange of member 14 is provided with at least three openings for

35 the reception of the upturned edge 18 of member 13 at the bottom in Figure 8. The upturned edge 18 serves as a rivet to hold members 13 and 14 in assembled relation. By means of this interconnection, the hub comprising parts 15 and 15a,

40 45 is secured to the center part 13 of reel side 11. The part designated by reference numeral 14 is provided with three upwardly extending lugs 19 which have been shown as spaced 120° apart and which are provided at their ends with projecting portions 20, as shown most clearly in Figure

7. The bottom 13 of side 10 is provided with three radial slots so positioned that lugs 19 can project through them. One of the radial slots has been shown in Figure 7 and designated by reference numeral 21. A plate 22 is positioned in the depression of side 10 and held in place by means of projections 23 cut from the cylindrical wall 12 and bent inwardly so as to overlap the outer edge of plate 22, as shown in Figures 2 and 4. Plate 22 has a central opening for the reception of the hub portion 15. Plate 22 is provided with two projections or lugs 24 that are cut from the material of the plate and bent outwardly forming what might be termed handles for use in turning it. Plate 22 is also provided with three openings 25 that are of keyslot form having one end of increased width as indicated at 26. The width of these openings at 26 is sufficient to permit the widened ends 20 of lugs 19 to pass through and the narrow portions of openings 25 are spaced closer than the width of the outer ends of the lugs and therefore when plate 22 is turned to the position shown in Figures 2 and 7, the two sides of the reel will become interlocked so as to form a reel that has the appearance of the ordinary reel, but which may be separated by turning plate 22 in a counterclockwise direction, when viewed as in Figure 2, until lugs 19 come to the wide ends 26 of openings 25, thereupon side 10, together with plate 22, may be removed from side 11 with its center portion 13 and the hub which is attached thereto by means of the rivets 18. When the parts are in assembled position, as shown in Figure 2, they are latched in this position by means of a plunger 27 that is mounted for reciprocation in a housing 28 as shown in Figure 6. A spring 29 is positioned between the inner end of the plunger and the closed end of the housing. A rod 30 connects the plunger with a head 31 that can be grasped by the operator. The inner end of head 31 has a pin 32 that will enter an opening in the end of housing 28, permitting the plunger to project through registering openings in the four plates as shown in Figure 6. This holds the parts secure in assembled position. When the reel is to be separated, plunger 27 is retracted sufficiently to bring the end of pin 32 to a position below the closed end of housing 28, after which head 31 may be rotated slightly bringing the pin out of register with the opening and this will hold the plunger in unlocking position, after which plate 22 may be rotated to bring the keyhole slots 25 to a position in which lugs 19 may pass through the widened end portions thereof. This releases the two sides of the reel and permits them to be separated, whereupon the film that is wound thereon may be easily and quickly removed. After the roll of film has been removed, the parts may be reassembled into the position shown in Figure 6 for the reception of more film. It is also possible to transfer a roll of film from one reel to another when reels having the construction shown in the drawing and described herein are used. Part 13 of the reel side 10 is provided with a lug 33 that serves as a stop and limits the angular movement of plate 22.

From the above description it will be evident that the reel which forms the subject of this invention and which has been described above is of a simple and substantial construction; that it can be readily assembled and disassembled; that when it is in fully assembled position, the parts are interlocked by means of plunger 27 so as to hold them securely and prevent any accidental separation thereof.

Particular attention is called to the fact that the two sides are duplicates and that they may be made by a single die. The offset part 16 can be put in by a separate operation and it is even possible to provide both of the reel centers with this offset if the additional operation necessary to offset one of the duplicate parts should make this desirable.

Having described the invention what is claimed 10 as new is:

1. A separable moving picture reel, comprising two circular sides, each having a circular central depressed portion, the bottom of each portion having a central opening, the two sides when in assembled relation with the bottoms of the portions facing each other, forming a reel for the reception of moving picture film, a central hub having an axial opening for the reception of a spindle, said central hub having a circular flange about its center, positioned between the bottoms of the first mentioned portions and rigidly attached to one of them, said flange having a plurality of lugs projecting from the free side thereof, said lugs having enlarged heads, the bottom of the other reel side having openings through which the lugs project, and means for latching the two sides comprising an annular plate positioned in the central depression of the said other side, means for movably interconnecting the plate with the wall of the depressed area to permit a limited angular movement, said plate having a plurality of keyhole slots positioned to receive the ends of the lugs, the narrow portion of said slots being movable into position between the hub bottom and the enlarged heads of the lugs to secure the two sides in assembled relation.

2. A separable moving picture reel comprising, two complementary side members, each of which has a central depression having a flat bottom and a cylindrical wall, the two side members when assembled with the bottoms of the central depressions in contact, forming a reel of which the two central depressions form hub receiving portions, the bottoms of the central depressed areas having central openings, a hub having an axial spindle receiving opening and an outwardly extending flange, the hub positioned in the openings in the bottoms of the central depressions, with the flange positioned between the bottoms, means securing the flange to one of the bottoms, the flange having a plurality of angularly spaced lugs with enlarged heads projecting from the free side thereof, the central bottom portion of the other depressed area having openings for the reception of the lugs, and means for interlocking the sides, comprising an annular latch plate positioned in the depressed area whose bottom has the lug receiving openings, said last named plate having a keyhole opening for each lug, the narrow portions being narrower than the width of the lug heads, whereby when the latch plate is in one rotary position, the parts will be interlocked, and hand grip lugs for use in turning the latch plate.

3. A separable moving picture reel, comprising, two circular sides, each having a circular depressed portion, the portions being in juxtaposed relationship, and movable means disposed between the outer face of one side and its depressed portion for removably securing the depressed portions together.

4. A reel in accordance with claim 3, including means disposed between the outer face of one side and its depressed portion for preventing movement of said movable means.

5. A reel in accordance with claim 4 wherein said movement preventing means is connected to one side of the reel and at least a portion of the securing means is connected to the other side.

6. A separable moving picture reel, comprising two circular sides, each having a circular central depressed portion, the portions being in juxtaposed relationship, means on one portion extending through apertures in the other portion for preventing angular movement between the two portions, and movable means selectively engageable with the means aforesaid for preventing relative movement between the portions in a direction laterally thereof.

7. A reel in accordance with claim 6 wherein the last named means is mounted for rotary movement on one portion.

8. A reel in accordance with claim 7, including means for preventing movement of the rotary means in a direction outwardly from the center of the reel.

9. A reel in accordance with claim 7, including means for locking the rotary means to the depressed portions in a predetermined position.

10. A reel in accordance with claim 7 including means for limiting the rotary movement between two predetermined positions.

11. A separable moving picture reel, comprising two circular sides, each having a circular central depressed portion, the portions being in juxtaposed relationship, means on one portion extending through apertures in the other portion for preventing angular movement between the two portions, means mounted for rotary movement on one portion selectively engageable with the means aforesaid for preventing relative movement between the portions in a direction laterally thereof, means for locking the rotary means to the depressed portions in a predetermined position, and stop means engageable with the rotary means for establishing the predetermined position.

12. A separable moving picture reel, comprising two circular sides, each having a circular central depressed portion, the portions being in

juxtaposed relationship, means on one portion extending through apertures in the other portion for preventing angular movement between the two portions, means mounted for rotary movement on one portion selectively engageable with the means aforesaid for preventing relative movement between the portions in a direction laterally thereof, and locking means mounted for movement in a direction laterally of said portions for locking the rotary means to the depressed portions in a predetermined position.

13. A separable moving picture reel, comprising two circular sides, each having a circular central depressed portion, the portions being in juxtaposed relationship, means on one portion extending through apertures in the other portion for preventing angular movement between the two portions, means mounted for rotary movement on one portion selectively engageable with the means aforesaid for preventing movement between the portions in a direction laterally thereof, and means for locking the rotary means to the depressed portions in a predetermined position, said locking means adapted to be moved to an inoperable position and be retained thereat.
